HEATING SYSTEM

Oscar A. Ross, New York, N. Y.

Original application November 15, 1927, Serial No. 233,482. Divided and this application December 17, 1934, Serial No. 757,790

27 Claims.

(CL 237—9)

This invention relates to heating systems and more particularly to major heating systems employed in large buildings wherein extensive radiation is installed.

One object of this invention is to furnish a major heating system wherein a number of comparatively small buildings, or a number of sections of a large building may have steam, or other heating fluid, supplied thereto in sequential order, in this manner reducing the maximum supply of steam, generally termed "maximum demand" to a comparatively small amount, as compared to the "maximum demand" required if all the small buildings, or sections of the large building were supplied with the steam simultaneously.

Another object is to furnish a heating system wherein the aforesaid "sequential supply of steam" will be effected automatically as well as in accord with the outside temperature whereby the buildings, or sections, will be uniformly heated irrespective of variations of said outside temperature.

Another object is to furnish a heating system for comparatively high buildings wherein the steam supplied to the system is "up-fed" at a comparatively high pressure to the point of distribution and thereafter reduced in pressure for supply to the heat radiators, in this manner permitting the use of comparatively small risers and reducing the loss by condensation therein.

Another object is to furnish novel forms of apparatus for accomplishing the results attained.

Other objects and advantages will appear as the description of the invention progresses and the novel features thereof will be pointed out in the appended claims.

The invention consists in such novel features, arrangements, combinations of parts and methods as are described in connection with the apparatus herein disclosed by way of example only. The novel methods are disclosed and claimed in my copending divisional application Ser. No. 233,482, filed November 15, 1927. Other features, embodiments and combinations of the apparatus hereinafter disclosed are also disclosed and claimed in my copending application Ser. No. 515,761, filed February 14, 1931, comprising a continuation of my application Ser. No. 56,283, filed September 14, 1925.

In describing the invention in detail, reference is had to the accompanying drawings, illustrating embodiments of the invention, and wherein like characters of reference designate corre-

sponding parts throughout the several views, and in which:

Figure 1 is a diagrammatic view of one form of heating system applied to a building; Fig. 2 is a perspective view of a portion of the apparatus associated therewith; Fig. 3 is a sectional view of another part of said apparatus; Fig. 4 is a diagrammatic view of still another part of the apparatus and Fig. 5 is a modified form of heating system shown diagrammatically.

Referring to Fig. 1, the building 1 is divided into three heated sections, 2, 3, and 4, each section having rooms a, b, and c supplied with a radiator 5, having thermally controlled outlet valve 6, room 2a being preferably supplied with a hot water radiator 8 receiving hot water from boiler 30 through riser 8a and discharging said water through return 8b. The radiators 5 in section 2 are fed by riser 9, those of section 3 by riser 10 and those of section 4 by riser 11. The condensation from said radiators is returned from section 2 by return 12, from section 3, by return 13 and from section 4 by return 14, said risers and returns being connected to sequential distributing unit 15, each return having a trap 16 at the discharge end thereof. Each heated section 2, 3, and 4, forms a subsidiary heating system of the major system supplying heat to building 1.

Steam is assumed to be supplied from a public utility service main 17 through pipe 18 and thence to valve 19, meter 20, reducing valve 21, automatic cutout 22, and valve 23 to sequential distributing unit 15. The condensation from returns 12, 13, and 14 passes through traps 16, unit 15 and pipe 25 to pump 26 of known form for removing air, or vapors, thence through pipe 27, pressure check valve 28, heating coil 29 of boiler 30, pipe 31, having pressure check valve 32, water meter 32a and thence to sewer 33.

Hot water heater 30 receives water from service main 34 and distributes hot water to faucets 7 through risers 35.

Traps 16 have a common air and vapor withdrawal line 36 connected to the vacuum end of the air discharge section of pump 26, the air being discharged to sewer 33 through pipe 37.

"Over-heat" thermostats 38 in sections 2, 3, and 4, are connected in multiple and arranged to energize automatic cut-off valve 22 for cutting off the steam supply upon any abnormal heating of said sections, a switch 39 manually controlling the flow of energy to wires 40, 41, and 42 of the circuit controlling said valve.

Referring to Figs. 2 and 4, showing sequential distributing unit 15 in more detail, motor 45 drives worm 46 engaging gear 47, mounted on shaft 48, also secured to which are distributor cams 2s, 3s, and 4s and return cams 2r, 3r, and 4r. The cam faces 49 of cams 2s, 3s, and 4s are adapted to depress valve stems 50 thereby opening supply valves 2sv, 3sv, and 4sv. The cam faces 51 of cams 2r, 3r, and 4r are adapted to depress valve stems 52 thereby opening return valves 2rv, 3rv, and 4rv. Valve stems 52 each support a contact spring 53 adapted to contact with contact 54 and establish the "pump motor circuit" as follows: from positive energy to switch 59, wire 55a, motor 55, wire 56, pipe 25, a contact 53 in lowered position, contact 54, wire 57 and switch 59 to negative energy.

Referring to Fig. 4, gear wheel 47 preferably formed of insulating material, supports contact sector 62 substantially encircling the side thereof, the contact springs 63 and 64 bearing thereon, a sector space 65 being provided sufficient to permit the opening of the circuit to motor 45 when spring 64 enters such space.

Located in the outside atmosphere, preferably on top of building 1, is thermostatic device 70, more fully described in my said co-pending application Serial No. 515,761, filed February 14, 1931, the rheostat arm 71 lowering to cut out resistance 73 upon the lowering of the outside temperature and raising to add resistance upon the increase of said outside temperature. Said device controls the "thermostat control circuit" as follows: from positive energy to wire 75, arm 71, a contact 72, resistance 73, wire 76, night switch 77, wire 78, motor 74, to negative energy through wire 79, in this manner varying the speed of motor 74 proportionately to the variation of the outside temperature. Motor 74 drives worm 83, rotating contact drum 84, supporting contact 85, adapted to momentarily bridge contact springs 86 and 87.

Motor 45 rotates cams 2s, 3s, 4s and 2r, 3r, and 4r through one heating cycle by establishment of the "heat supply circuit" as follows: from positive energy to wire 66, contact spring 63, contact 62, contact spring 64, wires 67, 68, motor 45 and wire 69 to negative energy. After gear 47 has completed a revolution in the direction shown by the arrow, contact spring 63 will enter space 65 thereby opening said circuit and motor 45 will stop. The relation of the space 65 and the various cams is such that motor 45 stops just after cam 4s has permitted valve 4sv to close and before valve 2sv is again opened. Likewise cam 4r permits the closing of valve 4rv and said motor stops before valve 2rv is again opened. After motor 45 has stopped, no flow of steam to, or flow of condensation from the system occurs and said motor remains stopped until contact 85 again bridges contact springs 86 and 87, whereupon the "frequency circuit" is established as follows: from positive energy to wire 90, contact spring 86, contact 85, contact spring 87, wires 91, 68, motor 45 and wire 69 to negative energy. As soon as motor 45 has again started contact 62 bridges contact springs 63 and 64 and energy is thereafter supplied from wire 66.

It is to be noted that each one of the contacts 72 has a dial indicating temperature of the outside atmosphere, and, if desired the rod 70a and spring 70b may be removed and arm 71 operated manually from handle 70c.

It is also to be noted that when the atmosphere 75 has reached 70 degrees the arm 71 will move to

the uppermost contact 72 to open the circuit to motor 74. If for any reason the arm should move onto said contact and motor 74 should stop with contact 85 bridging both springs 86 and 87, motor 45 would continue to operate for producing minimum heating. To avoid this unnecessary operation a contact spring 95 is arranged to engage contact 85 simultaneously with contact 86 whereby the "clearing circuit" is established as follows: from positive energy to wire 90, contact 10 spring 86, contact 85, contact spring 95, wires 96 and 78 to motor 74 and thence through wire 79 to negative energy. With this circuit established motor 74 operates until contact 85 has moved away from contact spring 86, in this manner also cutting off energy to motor 45 through contact spring 87.

Referring to Fig. 3, trap 16 comprises tank 100 provided with cap 101 supporting corrugated diaphragm 102, the interior of which communicates 20 with passageway 103 and pipe 36. This trap also includes check valve 104 constrained to seat by spring 105 permitting vacuum pipe 36 to withdraw air and vapors from the heating system through chamber 106 of tank 100, at the same 25 time creating a partial vacuum within diaphragm 102, whereby float 107, and valve 108 secured thereto and to said diaphragm, will be raised to empty trap 16. Valve 108 is biased in both extreme upper and lower positions by weight 109 30 secured to one arm of bell crank 110, the other arm of which is pivoted to float 107. The chamber containing diaphragm 102 is open to atmosphere through opening 111.

The operation of the trap is as follows: during 35 the "off" heating period of a section, as for example section 2, practically all the condensation collects in tank 100. As cam 2r acts to open valve 2rv and also starts pump 26, the vacuum produced by said pump causes a partial vacuum in the 40 diaphragm 102, also raises valve 104 and creates a partial vacuum in the pipe lines and radiators of section 2, it being assumed that the radiators 5 have cooled sufficiently to open valves 6. As tank 100 will contain considerable condensation, 45 the combined efforts of float 107 and diaphragm 102 will cause valve 108 to rise whereupon said condensation will flow to pump 26 and thence to heating coil 29 of hot water heater 30, said pump causes all air and vapors to be discharged to sewer 50 33 and the water to said heater and thence to the sewer. After tank 100 has been emptied and pump 26 stopped, the air leakage back through said pump will nullify the vacuum in pipe 36 and diaphragm 102, thereby again permitting valve 55 108 to seat and seal the return line preparatory to the next heating cycle and the accumulation of the resulting condensation produced thereby.

Referring to Figs. 1, 2, 3, and 4, the operation of the system disclosed thereby is as follows: assume the outside temperature surrounding building 1 to be approximately 40 degrees under which condition the arm 71 will be in contact with the 40 degree contact as shown, thereby establishing the "frequency circuit" whereby motor 74 rotates contact 85 to establish the "heat supply circuit" to motor 45 at a frequency whereby the resulting heat supply periods will be rendered at sufficiently close intervals to adequately heat building 1 with an exterior temperature of approximately 40 70 degrees.

After contact 85 has established the "heat supply circuit" and before gear 47 has rotated to again open said circuit as heretofore described, contact 85 will have moved sufficiently to have 75

opened said circuit between contact springs 86 and 87, and as space 65 of gear 47 passes under contact spring 64, motor 45 will stop in a manner to maintain all the supply valves 2r, 3r, and 4r closed until contact 85 again bridges contact springs 86 and 87.

If the outside temperature reaches 70 degrees or higher, and at which time no artificial heat is required in building 1, the arm 71 moves to the 70 degree contact whereupon the energy to motor 14 is cancelled by device 70, thereby also stopping the motor 45 indefinitely.

If the outside temperature falls to 10 degrees, arm 71 moves to the 10 degree contact 72 whereupon motor 14 operates at maximum speed thereby producing a maximum number of heating cycles by increasing the frequency thereof.

During each heating cycle produced by establishing the "heat supply circuit", and as motor 45 starts, cam 2r acts to open valve 2rv and drain section 2 of all condensation, thereafter the steam from pipe 18 is supplied to the subsidiary heating system of section 2 by action of the raised portion 49 of cam 2s in opening valve 2sv, said valve being maintained in open position for a period of time sufficient to fill all the radiators in section 2 with steam as well as maintain pressure therein until the radiator structure has attained a temperature substantially equivalent to that of the steam, whereupon said valve is closed.

A comparatively small interval of time after valve 2sv has closed, the raised portion 49 of cam 3s acts to open valve 3sv whereupon steam is supplied to radiators 5 of section 3 and after the subsidiary system therein has been filled with steam, said cam portion 49 of cam 4s acts to open valve 4sv whereupon steam is supplied to the subsidiary system in section 4 and as said last named raised portion 49 acts to close valve 4sv, the space 65 will have passed under contact spring 64 and motor 45 will be stopped with the raised portion 49 of cam 2s in a position to again effect the opening of valve 2sv. From the foregoing it will be noted that the steam has been supplied to the sections 2, 3, and 4, in sequential order during each heating cycle.

Substantially simultaneously with the opening of valve 2sv, as described, the raised portion 51 of cam 2r will have passed away from valve stem 52 of valve 2rv thereby closing said valve. As described, when valve stem 52 is lowered and contact spring 53 engages contact 54, the valve 2rv is opened and pump 26 is started thereby draining trap 16 of condensation as well as establishing a partial vacuum in the subsidiary system of section 2, and as supply valve 2sv opens, steam from supply pipe 18 will quickly fill said system, the thermally controlled valves 6 preventing the steam from entering the return 12 until the condensation thereof is effected.

A predetermined interval of time before cam 3s acts to open supply valve 3sv, the cam 3r will act to open return valve 3rv whereby trap 16 in return line 13 will be drained of its condensation and a partial vacuum will be established in the radiators 5 and risers 10 of section 3 prior to the opening of supply valve 3sv by cam 3s.

A similar sequence of operations will occur in draining condensation from and supplying steam to the subsidiary heating system of section 4 and thereafter motor 45 will stop until another heating cycle is initiated by establishing the "heat supply circuit" by contact 85.

From the foregoing it will be noted that by sectioning a building as 1, for heating purposes,

and supplying steam to a subsidiary heating system in each section sequentially, a comparatively small "maximum demand" of the steam is required thereby reducing the yearly "maximum demand" charge usually made by the concern supplying said steam.

The number of subsidiary heating systems and the radiation therefore is preferably proportioned whereby during the coldest weather, and upon the completion of a heating cycle, the drum 84 will have made a complete revolution and contact 85 will again establish the "heat supply circuit" in this manner producing a substantially continuous supply of heat to building 1, the supply calling for a comparatively low "maximum demand" from the source.

It is to be noted that the subsidiary heating systems of sections 2, 3, and 4, may be employed to heat detached buildings, one of the buildings containing the distribution apparatus 15 and auxiliary devices therefore.

In certain buildings where a comparatively small quantity of hot water is required, the surplus hot water from boiler 30 may be supplied to a hot water radiator 8 in room a, the cam 2s being adjusted to supply a proportionately lesser quantity of steam to the heating system in section 2.

Whereas pipe 36 connects the vacuum side of pump 26 to all the traps 16, the partial vacuum established in diaphragms 102 will not be sufficient to raise the valve 104 in other than the selected trap in which the condensation acting on the float will effect the raising of said valve.

Traps 16 are preferably of a capacity whereby substantially all the condensation from their correlated section, as 2, 3 or 4 will return before float 107 will rise with the assistance of diaphragm 102. The variable capacity of tanks 100 is preferably secured by insertion of fixed bodies 40 at 100a therein acting as liquid displacers.

If desired a rheostat 68a arranged to be varied by arm 68b insulatively supported by arm 71 and arranged to be shunted by switch 68c may be placed in series with motor 45 whereby said motor is slowed down as the outside temperature is lowered in this manner effecting comparatively longer supply periods of the steam to each section during each heating cycle, such longer supply periods, under certain conditions, being required to compensate for the more rapid cooling of the radiators during colder weather.

Whereas the raised cam faces 49 and 51 are shown as of a definite length, they may be made of variable length as shown in the Patent 1,178,170 to Marks, April 4, 1926.

The cam faces 49 of supply cams 2s, 3s, and 4s are preferably formed whereby the valves 2sv, 3sv, and 4sv opened thereby will remain open for a period sufficient to fill all the radiators as well as insuring that the radiator structure will assume a temperature substantially that of the steam therein.

The cam faces 51 of return cams 2rv, 3rv, and 4rv are preferably formed whereby the valves 2rv, 3rv, and 4rv are opened for a period of time sufficient to drain all the condensation from their correlated traps 16 and also permit the forming of a partial vacuum in the returns and radiators whereby rapid filling thereof occurs when the supply valves are opened.

Whereas the building 1 has been shown as sectioned in vertical planes, comparatively high office buildings, or similar structures are preferably sectioned in horizontal planes, the steam

being supplied to unit 15 at a comparatively high pressure and suitable reducing valves placed at the upper end of the risers for reducing the pressure of the steam as supplied to the radiators 5, this arrangement permitting the use of comparatively small capacity risers thereby reducing the condensation therein as well as reducing the cost of installation.

Whereas one return pump as 26 has been shown 10 for controlling all the flow of condensation, a similar pump may be employed for each section 2, 3, and 4, for independently controlling the flow of condensation therefrom and establishing the partial vacuum therein.

15 Whereas the steam supply has been shown as a public utility service main, a suitable steam boiler may be employed therefore.

Referring to the modified form of heating system shown in Fig. 5, the thirty-six story building 200, having basement 201, is shown as sectioned in horizontal planes A to J, each section being assumed to contain four floors 1, 2, 3, and 4, each floor having a heat radiating system 202 forming a portion of the subsidiary heating system supplied with low pressure steam from feeder line 210, said line receiving steam from high pressure riser 203 through reducing valve 204, each system being drained by a return 205.

In this major heating system, the subsidiary 30 heating system of each section A to J is preferably supplied with independent condensation and vacuum pumps 26 arranged to establish a partial vacuum in each subsidiary system just prior to the supply of the steam thereto.

35 Comparatively high pressure steam from public utility service main 11, or from high pressure boilers, is fed through distributing device 207 and through risers 203 to the reducing valves 204, thereby permitting the use of comparatively 40 small risers and reducing condensation.

The reducing valves 204 form the origin of the low pressure distribution to the subsidiary systems from whence the steam and condensation is "down-fed" through feeder line 210 and radiat- 45 ing system 202 to returns 205.

Owing to the larger volume of steam in the longer risers, as 203H and 203J, the distributor cams 49 of unit 207, are preferably formed to effect comparatively shorter time intervals of opening 50 the supply valves as 2sv, than the similar cams opening similar valves to the risers 203A and 203B, thereby equalizing the supply of steam by permitting the high pressure steam of the longer risers to expand into the subsidiary systems through the reducing valves 204.

Steam distributing unit 207, is similar to unit 15, being modified to include a larger number of supply and discharge valves, as 2sv and 2rv and correlated cams and circuit closers therefor.

60 A pipe 208 connecting each trap and correlated pump 26 corresponds the pipe 36 commonly connected to all the traps 16 of Fig. 1, and a pipe 209 commonly connected to all the air outlets of the pumps 26 conveys the air and vapors discharged 65 thereby to the sewer 33.

It will be understood that in the operation of the apparatus, on a decrease in outdoor temperature, more heat is supplied, but upon a corresponding increase in outdoor temperature, sub- 70 substantially a corresponding lesser amount of heat is supplied, and it is in that sense that the following claims have reference to variations in the heat supply or heat supply periods in accordance with variations in the outside temperature.

75 While the invention has been described with

respect to certain particular preferred examples which give satisfactory results, it will be understood by those skilled in the art, after understanding the invention, that various changes and modifications may be made without departing from the spirit and scope of the invention, and it is intended therefore in the appended claims to cover all such changes and modifications.

I claim:

1. In a heating system a source of pressured steam, a plurality of grouped spaces having radiators therein for heating the spaces, each group being arranged to receive steam from the source, control means for successively apportioning steam from the source to the groups whereby the groups are supplied with steam in sequential order, and means affected by variations in temperature of the atmosphere exterior of the spaces for varying the frequency of operation of the sequential control means.

2. In a heating system, a heat radiating system having normally closed valves in the supply and return line thereof, a source of pressured steam connected to the supply line, normally inactive means for draining the condensation from the system and establishing a partial vacuum therein, a device operating in cycles including means for effecting operation of the draining and vacuum producing means and opening the return valve during the initial portion of a cycle, means for cancelling the operation of the draining and vacuum producing means and closing the return valve during a subsequent portion of the cycle, means for opening the steam supply valve for filling the system with steam from the source during a subsequent portion of the cycle, means for closing the supply valve during the final portion of the cycle, and means for periodically effecting operation of the cyclic device.

3. In a heating system, a heat radiating system having normally closed valves in the supply and return lines thereof, a source of pressured steam connected to the supply line, normally inactive means for establishing a partial vacuum in the heat radiating system, a device operating in cycles including means for effecting operation of the vacuum producing means and opening the return valve during the initial portion of a cycle, means for cancelling the operation of the vacuum producing means and closing the return valve during a subsequent portion of the cycle, means for opening the steam supply valve for filling the system with steam from the source during a subsequent portion of the cycle, means for closing the supply valve during the final portion of the cycle, and means for periodically effecting operation of the cyclic device.

4. In a heating system, a heat radiating system having normally closed valves in the supply and return lines thereof, a source of pressured steam connected to the supply line, normally inactive means for establishing a partial vacuum in the heat radiating system, a device operating in cycles including means for effecting operation of the vacuum producing means and opening the return valve during the initial portion of a cycle, means for cancelling the operation of the vacuum producing means and closing the return valve during a subsequent portion of the cycle, means for opening the steam supply valve for filling the system with steam from the source during a subsequent portion of the cycle, means for closing the supply valve during the final portion of the cycle, and means for effecting varying periodic operation of the cyclic device in response

to variations in temperature of outside atmosphere.

5. In a major heating system having a plurality of subsidiary heat radiating systems, normally closed valves in the supply and return lines of the subsidiary systems, a source of pressured steam arranged to be connected to the receiving end of the supply lines, normally inactive devices associated with the subsidiary systems for establishing a partial vacuum therein, devices operating in cycles for each subsidiary system including means for effecting operation of the vacuum producing means and opening the return valves during the initial portion of a cycle, 10 means for cancelling the operation of the vacuum producing means and closing the return valves during a subsequent portion of the cycle, means for opening the steam supply valves for filling the system with steam from the source during another subsequent portion of the cycle, means 15 for closing the supply valves during the final portion of the cycle, and means for successively effecting periodic operation of the cyclic devices.

6. In a major heating system having a plurality of subsidiary heat radiating systems, normally closed valves in the supply and return lines of the subsidiary systems, a source of pressured steam arranged to be connected to the receiving end of the supply lines, normally inactive devices associated with the subsidiary systems for establishing a partial vacuum therein, devices operating in cycles for each subsidiary system including means for effecting operation of the vacuum producing means and opening the return valves during the initial portion of a cycle, means 20 for cancelling the operation of the vacuum producing means and closing the return valves during a subsequent portion of the cycle, means for opening and closing the steam supply valves for filling the system with steam from the source during another subsequent portion of the cycle, and means for successively effecting operation of the cyclic devices at intervals varied in response to variations in temperature of outside atmosphere.

7. In a heat radiating system having a supply line and a return line, a source of pressured steam, means for supplying steam from the source to the supply line, a trap in the return line arranged to receive condensation from the system, a normally closed valve for preventing discharge of condensation from the trap arranged to permit discharge thereof upon being opened, time controlled means for periodically producing a partial vacuum in the system and the trap and means for supplying the steam at time controlled intervals of the same frequency as the periodic production of the vacuum, and means affected by the vacuum produced by the vacuum producing means for opening the valve to discharge the condensation therefrom.

8. In a heat radiating system having a supply line and a return line, a source of pressured steam, means for supplying steam from the source to the supply line, a trap in the return line arranged to receive condensation from the system, a normally closed valve for preventing discharge of condensation from the trap arranged to permit discharge thereof upon being opened, time controlled means for periodically producing a partial vacuum in the system and the trap and means for supplying the steam at time controlled intervals of the same frequency as the periodic production of the vacuum, means affected by the vacuum produced by the vacuum

producing means for opening the valve to discharge the condensation therefrom, and means for opening the valve independently of the vacuum affected opening means upon a predetermined abnormal quantity of condensation accumulating in the trap.

9. In a heating system for a building having a plurality of stories heated by steam radiators, a source of high pressured steam at the base of the building, a high pressure riser extending upwardly from the source to substantially the uppermost portion of the heating system, a low pressure distribution system connected to the discharge end of the high pressure riser, the distribution system being arranged to downfeed the low pressure steam to the radiators, a reducing valve connected between the discharge end of the high pressure steam riser and the receiving end of the distribution system for automatically reducing the high pressure steam to a predetermined low pressure irrespective of variation in pressure of the high pressure source, means for conveying the low pressure steam and condensation from the radiators to the base of the building, and means for effecting supply of steam from the source to the high pressure riser during time controlled intervals alternately with cancelling the supply thereto during other time controlled intervals.

10. In a heating system for a building having a plurality of stories heated by steam radiators, a source of high pressured steam at the base of the building, a high pressure riser extending upwardly from the source to substantially the uppermost portion of the heating system, a low pressure distribution system connected to the discharge end of the high pressure riser, the distribution system being arranged to downfeed the low pressure steam to the radiators, a reducing valve connected between the discharge end of the high pressure steam riser and the receiving end of the distribution system for automatically reducing the high pressure steam to a predetermined low pressure irrespective of variation in pressure of the high pressure source, time control means for intermittently supplying steam from the high pressure source to the high pressure riser, and thermostatic means responsive to outdoor temperature changes for varying the relative lengths of the intervals of steam supply as compared with the spaces between such intervals.

11. In a heat regulating system, a steam heating system, a source of steam, means for effecting supply of steam from the source to the system for periods alternately with cancelling the supply for other periods, thermostatic means including means for varying the frequency of the steam supply periods in accordance with variations in temperature of the outside atmosphere and means for also varying the duration of the steam supply periods in accordance with variation in temperature of the outside atmosphere.

12. In a heat regulation system, a steam heating system, a source of steam, means for effecting supply of steam from the source to the system for periods alternately with cancelling the supply for other periods, thermostatic means including means for varying the frequency of the steam supply periods in accordance with variation in temperature of the outside atmosphere and means for also varying the duration of the steam supply periods in accordance with variation in temperature of the outside atmosphere, and means operable at will for eliminating the

thermostatic control as to the duration of the supply periods.

13. In a heat regulating system, a heating system including a supply line, a radiator, a condensation return line, a condensation trap and a motor driven condensation pump all connected in series relation, a source of steam, and a time interval device including means for connecting the source and the supply line for predetermined intervals alternately with interrupting the connection for other predetermined intervals, and means operating at intervals of a predetermined frequency relationship with said intervals of interruption for energizing the condensation pump motor for predetermined intervals alternately with deenergization thereof for other predetermined intervals.

14. In a steam heating system including steam radiators having supply and return passageways, a source of steam, a pump for producing a partial vacuum in the return passageway, another pump for exhausting the condensation from the return passageway, means for driving the pumps, means for supplying steam from the source to the supply passageway, time interval means operating in cycles, and means responsive thereto for rendering the pump driving means and the steam supply means active for predetermined periods alternately with cancelling the action thereof for other predetermined periods during each cycle, the active and inactive periods of the pump driving means being displaced in time with respect to the active and inactive periods of the steam supply means.

15. In a heating system having supply and return lines, a source of steam, means for supplying steam from the source to the system, means for producing vacuum in the return line, time interval means operating in cycles, and means responsive thereto for rendering the vacuum producing means and the steam supply means active for predetermined periods alternately with cancelling the action thereof for other predetermined periods during each cycle, the active and inactive periods of the steam supply means being displaced in time with respect to the active and inactive periods of the vacuum producing means.

16. In a heating system having supply and return lines, a source of steam, means for supplying steam from the source to the system, means including a pump for draining the condensation from the return line, time interval means operating in cycles, and means responsive thereto for rendering the condensation draining means and the steam supply means active for predetermined periods alternately with cancelling the action thereof for other predetermined periods during each cycle, the active and inactive periods of the steam supply means being displaced in time with respect to the active and inactive periods of the condensation draining means.

17. In a heating system having supply and return lines, a source of steam, means for supplying steam from the source to the system, means for producing vacuum in the return line, time interval means operating in cycles, means responsive thereto for rendering the steam supply means and the vacuum producing means active for predetermined periods alternately with cancelling the action thereof for other predetermined periods during each cycle, the active and inactive periods of the steam supply means being displaced in time with respect to the active and inactive periods of the vacuum producing means, and thermostatic means for varying the relative lengths of said

active and inactive periods of the steam supply means in accordance with variation in temperature of the outside atmosphere.

18. In a heating system having supply and return lines, a source of steam, means for supplying steam from the source to the system, means including a pump for draining the condensation from the return line, time interval means operating in cycles, means responsive thereto for rendering the steam supply means and the condensation draining means active for predetermined periods alternately with cancelling the action for other predetermined periods during each cycle, the active and inactive periods of the steam supply means being displaced in time with respect to the active and inactive periods of the condensation draining means, and thermostatic means for varying the relative lengths of said active and inactive periods of the steam supply means in accordance with variation in temperature of outside atmosphere.

19. A heating system for large buildings, comprising in combination, a plurality of adjacent risers, valves for each riser, motor actuated means for simultaneously turning on the valves of certain risers and turning off the valves on adjacent risers, and time controlled means for effecting the operation of said motors according to a predetermined schedule.

20. A heating system for large buildings, comprising in combination, a plurality of adjacent risers, valves for each riser, motor actuated means for simultaneously turning on the valves of certain risers and turning off the valves on adjacent risers, time controlled means for effecting the operation of said motors according to a predetermined schedule during normal working hours, and means for operating said time controlled mechanism on a different schedule for non-working hours.

21. A heating system for large buildings, comprising in combination, a plurality of adjacent risers, valves for each riser, motor actuated means for simultaneously turning on the valves of certain risers and turning off the valves on adjacent risers, time controlled means for effecting the operation of said motors according to a predetermined schedule, an outdoor thermostat, and means operable thereby for varying said time schedule according to outdoor temperature.

22. In a heating system for large buildings having a plurality of stories heated by steam radiators, said system including a plurality of subsidiary heating systems each comprising a group of radiators for serving a particular zone of the structure or structures heated, a local low pressure steam distribution conduit system for each of said groups, a plurality of high pressure steam risers running respectively from said source to the inlets of said low pressure distribution conduit systems, reducing valves connected respectively between the discharge ends of said high pressure risers and the inlets of said distribution conduit systems, and means for intermittently checking the flow of steam from said source to said risers during time controlled intervals alternately with the admission of high pressure steam to said risers during other time controlled intervals.

23. In a heating system for large buildings having a plurality of stories heated by steam radiators, said system including a plurality of subsidiary heating systems each comprising a group of radiators, a low pressure steam distribution conduit system for each of said groups and having a steam inlet positioned at substantially the

highest point of the subsidiary system of each group, a source of high pressure steam at the

7
rality of groups for serving respectively various zones of the structures to be heated, conduits run-

5. Within the building, a plurality of high pressure steam risers, originating respectively from said source 5 to said source and low pressure distribution conduits, each having valves connected respectively between the discharge ends of said high pressure risers and the inlets of the distribution conduit systems, time controlled means for inter-

10. mittently checking the supply of steam from said source to said risers respectively at interspaced intervals, alternating with intervals of supply of high pressure steam to the risers, and thermostatic means responsive to outdoor temperature 15 changes for varying the relative lengths of the intervals of steam supply as compared with such intervals of checking of the supply.

24. Regulating apparatus for steam heating systems having radiators located in rooms to be 20 normally maintained at desired substantially uniform temperatures while affected by variations in outdoor temperature, comprising a source of steam, said radiators being divided into a plurality of groups for serving respectively various zones of the structures to be heated, conduits 25 originating respectively from said source to said groups, time controlled means for intermittently supplying steam from said source to the conduits for each of said groups respectively at substantially interspaced intervals, and thermostatic means responsive to outdoor temperature changes for varying the relative lengths of the intervals of steam supply as compared with the spaces between such intervals.

25. Regulating apparatus for steam heating systems having radiators located in rooms to be 20 normally maintained at desired substantially uniform temperatures while affected by variations in outdoor temperature, comprising a source of steam, said radiators being divided into a plu-

ning respectively from said source to the conduits for each of said groups respectively at substantially interspaced intervals, and means for intermittently supplying steam from said source to the conduits for each of said groups respectively at substantially interspaced intervals, normally of sufficient frequency to enable substantially continuous maintenance of predetermined temperatures in the structures heated.

26. In a heating system, a source of steam under pressure, a plurality of grouped spaces having radiators therein for heating the spaces, conduits for conveying steam from said source to the radiators of each of said groups respectively, valves in said conduits for controlling the flow of steam to each group respectively, and means common to said valves for controlling the operation of the same in sequential order to alternately admit and check the flow of steam to each of said groups, whereby the steam is successively apportioned from said source to the several groups.

27. In a heating system, a source of steam under pressure, a plurality of grouped spaces having radiators therein for heating the spaces, conduits for conveying steam from said source to the radiators of each of said groups respectively, valves in said conduits for controlling the flow of steam to each group respectively, and time controlled means common to the valves and intermittently controlling the operation thereof, to admit supplies of steam to said groups respectively in succession, whereby the steam is successively apportioned from the source to the various groups and steam is supplied to one group during intervals of interruption of the supply to another group.

OSCAR A. ROSS.
